UNITED STATES PATENT OFFICE

JOHN PRESTON MINTON, OF WHITE PLAINS, AND ABRAHAM S. RINGEL, OF BROOKLYN,
NEW YORK, ASSIGNORS TO RADIO CORPORATION OF AMERICA, A CORPORATION OF
DELAWARE

ACOUSTIC DEVICE

Application filed July 20, 1925. Serial No. 44,735.

This invention relates to acoustic devices for use in reproduction of voice, music or other signals. It has for its object also the truer and more exact reproduction, constancy

5 of volume and in general more faithful likeness to the original than heretofore.

It has been known that whenever a vibration was impressed upon any vibratile body that there are certain frequencies at which 10 reproduction will be most efficient while at all others more or less inefficiency occurs resulting in exaggeration of certain tones as well as other undesirable effects. This invention attempts to obviate these difficulties by so arranging 15 the oscillatory member or members that different elements thereof will respond at their most efficient period of vibration at different frequencies thereby causing the reproduction to be more uniform and of a more 20 constant volume as well as giving greater sensitivity and efficiency.

This invention also relates to telephony, telegraphy, and their other allied arts. More specifically the arrangements herein disclosed 25 represent what is commonly known as loud speakers or electrical reproducers and the like although it is not intended to limit its use to this particular field. It might as well be used with phonographs and other resonant rever- 30 berating systems. It is also useful wherever large amplitudes of vibration are desired at or within the audio frequency range which must necessarily be of constant value.

Other objects and advantages will be apparent upon reading the following disclosure including specification, claims and annexed drawings.

The various figures of the drawings show different specific details as follows:—

40 Fig. 1 shows the front view of one modification.

Fig. 2 shows a cross section of this modification along lines II—II of Fig. 1.

Fig. 3 shows a different adaptation of the 45 same idea.

Fig. 4 shows a cross section of the adaptation of Fig. 3 along the lines IV—IV.

Figs. 5 and 7 are graphs of various characteristic curves of some of these arrangements.

50 Fig. 6 shows a simplified arrangement.

Fig. 8 shows, in detail, one of the elements used in Fig. 2 or any detail.

Fig. 9 shows another eddy-current operated device.

These figures make use of various and differently constructed oscillatory elements attached to the same vibrating system. 1 and 2 of Fig. 1 show two such members mounted in a mounting plate 3 which serves to prevent the vibrations at the rear from affecting those in front. In one instance 1 may be in the form of a diaphragm held rigidly at its periphery while 2 is a conical member loosely mounted in the mounting plate 3 by means of a thin sheet 11 of fabric, rubber or leather. 60 These two vibratile members are both connected to a common vibrating system by means of connections 12, 17 and 18. 12 may be a light weight rigid spider or other equivalent construction. The lever 7 of the vibrating system is suspended at 16 about which it freely oscillates. The lever is actuated by the flow of current through the coil 5 mounted on the permanent or electromagnet 8 which causes motion of armature 9 connected to the lever 7 by means of a pivot connection 13. The connections 17 and 18 are fastened to lever 7 by means of pivots 14 and 15. 70

From this construction it can be seen that these two elements may have different characteristics which so cooperate as to produce a sound which may be more nearly constant for a given range of frequencies. The cone 2 may be constructed of some semi-rigid fabric such as paper, parchment, cardboard or other membranous material. The cone or diaphragm 1 may be stretched or held loosely and may be of metal or the same material as the cone 2. The characteristics of this arrangement will be discussed further in connection with Fig. 5. 1 may also be composed of a compound cone and loosely mounted by similar material 11. This cone can be adjusted in such a way that the most pronounced frequencies at which it responds may be varied throughout the range. This is done by an adjustment 10 connected between the two sections of the member. 80

21 and 22 of Figs. 3 and 4 are also diaphragms constructed of similar material and 100

mounted in a similar way as cone 2; 11 being resilient fabric. This fabric is connected to the cylindrical members 19 and 20 which support these cones 21 and 22 to some extent, and 5 serve to prevent vibrations from the rear of the cones from effecting those on the front. 25 is a magnet permanently or otherwise energized by coils 26 and 50 and 27 and 28 are actuating coils for cones 21 and 22 respectively and are rigidly connected thereto. 10 These coils 27 and 28, located in their respective flux gaps of the magnet 25 are very sensitive to the slightest change in current. It is not intended to limit this arrangement to the use of cylindrical mounting members but the cones might as well be mounted as in Figs 1 and 2. 23 is a flexible disc with spirally cut holes to give it added resilience. It is fastened at its center by 15 means of a screw or rivet 24 to the middle pole of magnet 25 and helps to center the vibrating system.

If the apparatus shown in Figs. 2 and 4 be analyzed and the characteristics of their various elements be plotted taking the audibility as ordinates and the frequency in cycles per second for abscissa, curves something like those shown in Fig. 5 will result. Curve I shows a characteristic of cone 1 of Fig. 2 or 20 cone 22 of Fig. 4 and curve II shows that of cone 2 of Fig. 2 or cone 21 of Fig. 4. If these two cones in either modification are operated jointly by the same source or by the same current the two characteristic curves will be 25 superimposed upon each other giving a resultant curve III which shows a smaller percentage of variation and no valleys as *a* and *b*. By adjusting diaphragm 1 of Fig. 2 through adjusting nut 10 the characteristic 30 curve I can be shifted horizontally along the abscissa to such a position that it will most completely eliminate the silent periods or valleys.

These two ideas may be combined into one 45 structure as shown in Fig. 6 where 3 is the mounting plate, 11 the flexible strip and 29 and 30 are the oscillatory elements. The diaphragm 30 is rigidly connected to the cone 29 and vibrates with it. It is actuated 50 by the magnets 32 but separated therefrom by means of pads springs or other similar devices 31.

The characteristics of this structure are 55 shown in Fig. 7 where I' shows the characteristic of the cone 29 and II' that of the disc or diaphragm 30. In this case the valley *a'* is filled by the hump in the curve II' thus producing the more nearly constant response shown in III'.

60 The adjustable feature of 1 in Fig. 2 is shown in detail in Fig. 8 where 10 is the adjusting mechanism comprising threaded shaft 36 on the adjusting bushing 39 and locknut 38 being threaded on the shaft 36. 65 The end of this shaft is connected to seat 40

which is attached to the cone 35. The two cones 34 and 35 may have the same slope or different slopes to render them resonant to different frequencies as desired and are fastened together and flexibly mounted in the 70 casing 44 by means of element 46 which may be similar to 11. The cover 45 is screwed into the casing 44 to conduct the sound or may be omitted as desired. The member 46 is clamped by means of bolts 47. The cones 75 may be set in vibration by means of magnet 42 connected to casing 44 by the screws 48 and operates on the armature 41 which is rigidly attached to the cone 35.

By means of the shaft 36 different tensions 80 may be applied to the compound cone either in contraction or expansion thereby changing the periods at which it responds most efficiently. In this way the characteristics may be varied at will.

Another modification of this idea is shown in Fig. 9. As in the case of Fig. 4 a similar magnetic structure 49 is used with the exception of the location of the actuating coils 51 and 53 which are mounted in the pole 85 pieces themselves instead of being mounted on the cones. The magnetic structure 49 may be either permanently or electrically energized as by means of coils 26 and 50. The current through these coils must be direct in 90 order to give approximately constant flux.

The flux produced through the air gaps passes between the respective pole pieces. In the air gaps are located cylindrical sleeves 52 and 57. These sleeves may be of copper, 100 aluminum or other low resistant electrically conductive material, or may be in the form of multi-turn short circuited coils mounted on proper brackets. As shown in the figure, cylindrical sleeves are used, riveted by means 105 of rivets 55 to different parts of the cone 54 or fastened by any other suitable means.

It has been found best to make these sleeves as light as possible in order that they 110 may respond to high frequencies more readily without absorbing too much energy by their inertia. As shown sections 56 are cut out to decrease their weight. Other elements 3 and 11 are the same as formerly described. Cone 54 may also be the same as the cones 115 used before.

In the operation of this modification a variable alternating type current is caused to flow in the coils 51 and 53 in accordance with the vibrations which are desired to be impressed upon the cone 54. This change in current will cause the flux flowing across the gaps due to the coils 26 and 50 to be shifted back and forth in a direction parallel to the sleeves 52 and 57. Due to the fact that these sleeves are of conducting material eddy currents will be set up in the sleeves which attempt to counteract this effect. In this attempt a reaction will be exerted upon the sleeves themselves moving them with the vi- 120 125 130

brations of the flux thus moving the cone correspondingly.

As shown the sleeve 52 is connected to an outer part of cone 54 and therefore will produce a greater response to vibrations of lower frequency while sleeve 57 being connected to one end of the cone will be more responsive to vibrations of a higher frequency producing nodes and anti-nodes along the length of 10 the cone 54. It can thus be seen that the two actuating sleeves will, in connection with the cone be responsive to different resonant frequencies thereby causing a more constant response than would be obtainable with a single 15 operator. The characteristics of this system would be similar to those described in connection with Figures 3, 5 and 8.

Any other combination arrangements of different vibrating systems may be used as 20 for instance cone 1 of Fig. 2 may be used in conjunction with the device of Fig. 4 or with a diaphragm. Three or more vibrating systems may also be used in order to make the audibility curve more constant in value over 25 a very wide frequency range. With such a combination, is used a longer lever 7 as the case may require and the various systems may be attached at expedient points. Each system might also have its individual operator 30 such as a magnet and armature and the operators connected into the same circuit. It is not intended to limit the constructions of these arrangements to the specific modifications shown but any other elements may be 35 used which are well known and the characteristics of which are known to take the place of those shown. The greater the number of elements used and the more diversified their maximum values of audibility are in respect 40 to frequency, the more constant will be the response. This arrangement also could be used with a phonograph or other similar device by attaching a needle or reproducer to the oscillating system in a well known 45 manner.

I request protection according to the following claims:—

1. The method of reproducing oscillations 50 of different frequencies which consists in impressing these oscillations upon elements having different natural responses and combining the responses thus produced whereby a constant response results and preventing the oscillations developed on both sides of the 55 elements from intermingling.

2. A method of producing oscillations 60 which consists in vibrating a resonant body having a period of minimum response between two periods of maximum response, and producing other oscillations which are most effective at the period of minimum response.

3. A method of producing oscillations 65 which consists in vibrating a resonant body having a period of maximum response at a low frequency and a second period of maxi-

mum response at a high frequency and in simultaneously vibrating a second resonant body having a period of maximum response intermediate the periods of maximum response of the first mentioned resonant body. 70

4. In combination, a vibratile element having a maximum response at low frequencies and also at high frequencies, a second vibratile element having a maximum response at intermediate frequencies and means for vibrating both elements simultaneously. 75

5. An acoustic device comprising a vibratile element having a maximum response at low frequencies and also at high frequencies, a second vibratile element having a maximum response at intermediate frequencies and a single mechanism for vibrating said elements simultaneously and in phase. 80

6. In combination, a vibratile element having a maximum response at low frequencies and also at high frequencies, another vibratile element having a maximum response at intermediate frequencies, means for vibrating both elements simultaneously whereby a constant response may be obtained and means for adjusting one of the elements to vary its period of maximum response. 85

7. An acoustic device comprising a vibratile element having a maximum response at low frequencies and also at high frequencies, a second vibratile element having a maximum response at intermediate frequencies, and means for vibrating said elements simultaneously, said means comprising a lever pivoted at one end, a driving unit connected to said lever intermediate its ends, and connections from said lever to said vibratile elements. 95

8. In combination a vibratile element having a maximum response at low frequencies and also at high frequencies, another vibratile element having a maximum response at intermediate frequencies, means for vibrating both elements simultaneously at the same frequency whereby a constant response may be obtained, and means for adjusting one of the elements to vary its period of maximum response, one of the elements having a flexible support. 105

9. A vibratile member for an acoustic device comprising a pair of conical diaphragms positioned with their edges adjacent each other and means adjustable from outside of said diaphragms for tensioning said diaphragms. 115

10. A vibratile member for an acoustic device comprising a pair of conical diaphragms positioned with their edges adjacent each other and means for tensioning said diaphragms, said means comprising a member fixedly secured to the apex of one conical diaphragm and adjustably secured to the apex of the second conical diaphragm. 125

11. An acoustic device comprising a casing, a vibratile member, resilient means for sup-

porting said vibratile member in said casing, said vibratile member comprising a pair of cones positioned with their edges in contact with each other and with their apexes joined by means of an adjustment member, one end of said adjustment member comprising an armature, and a driving unit secured to said casing and cooperating with said armature.

12. In an acoustic device, a diaphragm 10 mounted for vibration, a lever of the third class, means connecting said diaphragm with said lever, and means for vibrating said lever.

13. An acoustic device comprising a diaphragm of the type adapted to radiate sound 15 waves directly to the open air, a driving unit, and means for operatively connecting said diaphragm with said driving unit, said means comprising a lever pivoted at one end and connected to said diaphragm at its other end 20 and to said driving unit at a point intermediate its ends.

14. In an acoustic device, a diaphragm mounted for vibration, a second diaphragm mounted for vibration, a lever pivoted at one 25 end, means connecting the first mentioned diaphragm to said lever, means connecting said second diaphragm to said lever, and a driving unit connected to said lever.

15. An acoustic device comprising a mounting 30 provided with a plurality of openings, a diaphragm for each opening, flexible means for supporting said diaphragms within said openings, and means for vibrating said diaphragms simultaneously.

35 16. An acoustic device comprising a mounting provided with a plurality of openings, a diaphragm for each opening, flexible means for supporting said diaphragms within said openings, and a single means for mechanically 40 vibrating said diaphragms simultaneously and in phase.

17. A vibratile unit for an acoustic device comprising a vibratile element of conical formation and a diaphragm connected therewith.

45 18. A vibratile unit for an acoustic device comprising a frustum and a diaphragm secured to one end thereof.

19. In an acoustic device, a vibratile unit comprising a tapered portion and a plane 50 portion secured to one end thereof, and means for vibrating said unit.

20. A vibratile unit for an acoustic device comprising a conical portion having a maximum response at low frequencies and also at 55 high frequencies, and a flat portion secured to said conical portion, said flat portion having a maximum response at intermediate frequencies.

60 21. An acoustic diaphragm comprising two circular metallic sheets joined together at the periphery of one of said sheets, and screw means associated with said sheets to adjust the tension therein and to hold said sheets in spaced and fixed vibratory relation.

65 22. An acoustic diaphragm comprising two

sheets of thin material juxtaposed to form a hollow vibratory member decreasing in thickness from its centre toward its periphery, means for simultaneously separating and stretching said sheets, said means being supported solely by said vibratory member and vibratile therewith.

70 23. The combination of an acoustic diaphragm, comprising two sheets of thin material, means for securing said sheets together at their peripheries and rigidly supporting them, and means for separating the centers of said sheets and holding them in fixed vibratory relation with respect to each other, said means being adjustable to vary the distance between the centers of said sheets and thereby vary their tension.

75 24. A loud speaking diaphragm comprising a stretched flexible sheet held constantly under tension along its surface, and a driving member connected to the center of said diaphragm, the normal tensioned condition of the diaphragm imposing substantially no pull or push load on the driving member.

80 25. A sound reproducer comprising a membrane, means for holding the same constantly under tension along its vibratory surface; and a driving unit connected to the center of said membrane which is supported under tension independently of said driving unit.
